C. RODERICK & T. L. KNAPP,
MEANS FOR SECURING TYPE WRITERS TO BASE BOARDS,
APPLICATION FILED JULY 1, 1910.

Patented May 8, 1917.

2 SHEETS—SHEET 2.

UNITED STATES PATENT OFFICE.

CHARLES RODERICK AND THERON L. KNAPP, OF WOODSTOCK, ILLINOIS, ASSIGNORS TO THE OLIVER TYPEWRITER COMPANY, OF CHICAGO, ILLINOIS, A CORPORATION OF ILLINOIS.

MEANS FOR SECURING TYPE-WRITERS TO BASE-BOARDS.

1,225,057.

Specification of Letters Patent.

Patented May 8, 1917.

Application filed July 1, 1910. Serial No. 569,960.

To all whom it may concern:

Be it known that we, CHARLES RODERICK and THERON L. KNAPP, citizens of the United States, and residents of Woodstock, 5 in the county of McHenry and State of Illinois, have invented certain new and useful Improvements in Means for Securing Type-Writers to Base-Boards; and we do hereby declare that the following is a full, clear, 10 and exact description thereof, reference being had to the accompanying drawings, and to the letters of reference marked thereon, which form a part of this specification.

This invention relates to typewriting machines and is more particularly applicable 15 to machines of the "Oliver" type in which the shift-frame is provided with two horizontal, transversely arranged guide-bars on which the paper-carriage rests and travels 20 and in which said guide-bars project at their ends beyond the shift-frame proper and extend laterally outside of the frame where they are supported from a base-board beneath the machine frame. The type of machine referred to is illustrated in Letters 25 Patent Number 904,207, of the United States, granted November 17th, 1908, to Theron L. Knapp.

The object of the invention is to provide 30 simple and efficient means for securing the machine frame to the base-board which will, at the same time, afford a cushion to decrease the shock and deaden the noise due to the operation of the machine and will accurately maintain said machine frame in 35 its proper relation with respect to the supports for the extended guide-bars.

In the drawings:—

Figure 1 is a top plan view of a machine 40 of the type described, with the paper-carriage and type-keys removed and the vertical bars which support said type-keys shown in cross-section.

Fig. 2 is a partial vertical section on an 45 enlarged scale through Fig. 1 on the line 2—2 thereof.

Fig. 3 is a vertical section through Fig. 1 on the line 3—3 thereof.

Fig. 4 is a partial vertical section on an 50 enlarged scale on the line 4—4 of Fig. 1.

Fig. 5 is a vertical section through Fig. 4 on the line 5—5 thereof.

As shown in the drawings, 10 is the base-board; 11, the machine frame; 12, the shift-

frame; 13, 14, the extended guide-rods for 55 the paper-carriage which are connected to the shift frame and project laterally beyond the machine frame; and 15, 15, 15^a, 15^b, the supports for the ends of the guide-bars said supports being secured to the base- 60 board. These parts are substantially as described in the patent referred to and need no further description as they form no part of the present invention.

The machine frame base 11 is preferably 65 made hollow and has a top wall 21 and an upright flange 21^a. 16, 17, 18, 19, indicate toe-clamps which are secured to the base-board 10 in position to engage against the upright flange 21^a of the base 11 of the machine frame. Said toe-clamps are preferably 70 arranged in pairs with one pair forward of and the other pair back of the transverse medial line of the machine, and with the toe-clamps of each pair in a line 75 parallel to the guide-bars 13, 14. Each of said toe-clamps consists of an angular piece of metal having a horizontal member 16^a which engages the top of the base-board, and an upright member 16^b which engages 80 the outer surface of the upright wall of the machine base. The horizontal members 16^a are provided with holes for screws 22 by means of which they are secured to the base- 85 board. It is apparent that the toe-clamps 90 form rigid abutments rising from the base-board which will positively resist any tendency of the machine frame to twist or shift on the base-board in the operation of the shift-frame.

The base 11 is anchored or held to the base-board by the following means: In the vertical plane of the longitudinal central axis of the machine frame, near the front of the same, there is secured to the underside of 95 the top 21 of the base, a lug 23, (see Figs. 1, 4 and 5). Said lug is preferably provided with lateral flanges 23^a, 23^b having holes or openings to receive screws 23^b, 23^a, which are threaded into the top 21 of the base. 24 100 is a recess opening through the bottom of said lug and internally threaded to receive the upper end of a threaded bolt 25 which projects upwardly from the base-board and is located in a vertical hole 26 in the base- 105 board. Said hole is enlarged at the bottom to form a recess 26^a to receive the head 25^a of the bolt and a washer 27 against which

said head directly bears. The base of the lug 23 is substantially on a level with the lower margin of the upright flange 21^a of the base and rests on an elastic washer 28 5 interposed between its base and the top of the base board 10. This construction efficiently anchors or holds the machine base at this point to the base board and at the same time affords a cushion bearing for said 10 base.

Similar anchoring and cushioning devices are located at the rear of the machine at points spaced equally on each side of the longitudinal central axis of the machine base 15 (see Figs. 1 and 2). In this case the upright wall of the base is preferably thickened at the point of anchorage to form a lug 33. Said lug is provided as before with a vertical internally threaded recess 34 to 20 receive a vertical threaded bolt 35 which projects upwardly from a hole 36 formed in the base-board. 38 is the cushioning washer interposed between the base of the lug and the top surface of the base-board. On account of the increased depth of the upright 25 flange 21^a at the rear of the base, the bolts 35 may be made longer than the bolt 25.

It is apparent from the above description that the bolts 25, 35, 35 may be drawn home 30 so as to efficiently anchor the machine to the base-board and hold it securely against overturning without impairing the efficiency of the cushioning members 28, 38, 38, and that

any tendency of the machine to twist or shift on the base-board, made possible by the elasticity of this anchorage, is prevented by the 35 toe-clamps 16, 17, 18 and 19.

We claim as our invention:—

The combination of a typewriting machine having a base portion provided with substantially upright side walls and fastener lugs rigid with said base portion, a base board, cushioning members interposed between said lugs and said base board for holding said machine base out of contact 40 with said board, fastener bolts extending vertically through said base board and said cushioning members and engaging said lugs to loosely secure said machine base to said base board, and a plurality of abutments 45 rigidly secured to said base board and having upwardly projecting portions engaging the side walls of said machine base to securely hold the same against lateral movement while permitting a limited vertical 50 movement thereof relative to said base board, substantially as described.

In testimony, that we claim the foregoing as our invention we affix our signatures in the presence of two witnesses, this 17th day 55 of June, A. D. 1910.

CHARLES RODERICK.
THERON L. KNAPP.
